UNITED STATES PATENT OFFICE

ROBERT L. DAINÉ, OF NEW YORK, N. Y., AND RENÉ GUYÉ, OF NEUCHATEL, SWITZERLAND, ASSIGNEES, BY DIRECT AND MESNE ASSIGNMENTS, TO THE TELEREGISTER CORPORATION, OF NEW YORK, N. Y., A CORPORATION OF DELAWARE

QUOTATION BOARD OR THE LIKE APPARATUS

Application filed January 13, 1928. Serial No. 246,474.

This invention relates to quotation indicating boards and the like apparatus such, for example, as brokers' stock or commodity quotation boards, the invention being particularly applicable to automatic electrically operated equipment of this class.

The objects of this invention include the provision of apparatus and equipment of the above-indicated class which will be adaptable 10 with a wide degree of flexibility to various conditions and which will be dependable, relatively simple and efficient.

Various further and more specific objects, features and advantages will clearly appear 15 from the detailed description given below, taken in connection with the accompanying drawings, which form a part of this specification and illustrate, merely by way of example, several embodiments of the invention.

20 The invention consists in such novel features, arrangements and combinations of parts as may be shown and described in connection with the apparatus herein disclosed by way of example only and as illustrative of preferred arrangements.

In the drawings, Fig. 1 is a front view, partly broken away, showing an assembled group of demountable sections comprising 25 a broker's stock quotation board illustrating an embodiment of the invention;

Fig. 2 is a vertical sectional view, partly broken away, of a board such as shown in Fig. 1;

Fig. 3 is a plan view showing a demountable group of indicating units such as may be comprised in a board as of Fig. 1;

Fig. 4 is an end elevational view of the devices and the parts shown in Fig. 3;

Fig. 5 is a plan view, partly in section, showing a detachable plug which may be used in connection with leading-in wires to a board as of Fig. 1;

Fig. 6 is a front elevational view of an indicating unit of the type shown in Figs. 3 and 4;

Fig. 7 is a front elevational view, partly broken away and in section, showing one manner of constructing the demountable board sections;

Fig. 8 is a sectional view taken substantially along the line 8-8 of Fig. 7;

Fig. 9 is a front elevational view, partly broken away and in section, showing another manner of constructing the demountable board section;

Figs. 10 and 11, respectively, are sectional views taken substantially along the line 10-10 and 11-11 of Fig. 9;

Fig. 12 is a horizontal sectional view 60 through a modified form of detachable indicator;

Fig. 13 is a rear view partly broken away showing an assembled broker's board utilizing indicators as of Fig. 12;

Fig. 14 is a vertical section through a modified form of container;

Fig. 15 is a rear view similar to Fig. 13 showing the use of containers such as shown in Fig. 14;

Fig. 16 shows the face of a broker's board constructed according to either of the modifications as of Fig. 13 or Fig. 15; Fig. 17 shows a broker's board partly in longitudinal section on three different planes illustrating the construction of the containers shown in Figs. 12 and 13 and their relation to the frame of the board; and

Fig. 18 is a view similar to that shown in Fig. 17 showing the containers illustrated 80 in Figs. 14 and 15.

Referring to Fig. 1, it will be noted that a broker's board is provided to exhibit quotations in substantially a conventional arrangement. The board here shown may comprise 85 a plurality of sections as, for example, at 20, 21, 22 and 23, which are demountable with respect to each other. These sections may be arranged in a plurality of side-by-side tiers resting upon a suitable supporting frame, as 90 at 24. The sections of each tier may rest one upon another. A typical board might be made up of sections each having indicators for exhibiting the fluctuating quotations of ten stocks. Five of such sections may be conveniently arranged one on top of another to form a tier, and then two of such tiers side by side would have a capacity for quoting one hundred stocks or other items.

Along the top edge of each section, space 100

may be provided, as at 25, for painting or otherwise applying the conventional abbreviations indicating which stock or other item is being quoted by the indicators immediately below in the same section. At the left-hand side of the board a suitable section of sheet material, as at 26, may be secured upon which may be painted or otherwise indicated the conventional indicia such as to indicate the "Open", "High", "Low" and "Last" quotations of any particular item as well as corresponding indicia denoting yesterday's "High", "Low" and "Closing" quotations. Since the numbers exhibiting the previous day's quotations are ordinarily changed but once each day, such numbers may conveniently be of the ordinary manually changeable type comprising interchangeable slips of cardboard or other material bearing numbers, such slips being retained upon the board in a conventional manner in slots as, for example, indicated at 27 in Fig. 2.

On the other hand, for the fluctuating quotations automatic changeable indicating units may be provided as shown in Figs. 3, 4 and 6, and the same will be hereinafter described in detail. Where the board is to be used for New York Stock Market quotations, each quotation, such for example as the opening quotation of a particular stock, ordinarily may require the use of four digit indicators, respectively, for the hundreds, tens, units and fraction values, and therefore where four quotations, namely, "Open", "High", "Low" and "Last", are to be simultaneously exhibited, a total of sixteen digit indicating units must be provided. According to the arrangement shown in Fig. 3, such digit indicating units may be conveniently arranged in groups of four, each group comprising the units necessary for one quotation of one stock, and in the embodiment here shown, each of such groups of four is arranged to be quickly demounted in respect to the larger demountable sections. Furthermore, as will be hereinafter further explained, individual indicator units of each of such groups of four may also be readily demounted. The demountable features of the sections, groups of units, and units include not only the features of the mechanical supporting structure but the electrical connections, in each instance may, if desired, be simultaneously demounted substantially without interference with the electrical connections to adjacent sections or units, as the case may be.

Such demountability in respect to the mechanical and electrical features not only makes it possible to quickly inspect, repair or replace any section or unit, but such features are of particular advantage in connection with an automatic electrically operated broker's board for numerous other reasons. If the quotations of a large number of stocks are exhibited with sixteen digit indicating

units used for each stock, the necessary multitude of units may, according to this invention, be standardized and made interchangeable. Furthermore, the sections being separable may be arranged to best suit the requirements of the broker and so as to best fit into the space available at his office. For example, a number of tiers greater or smaller than two may be arranged, or if the broker's space is relatively narrow, a large number of sections may be placed one on top of another. Also, if necessary, the sections of one tier may be placed at an angle to those of another tier to best fit the space available. As the number of stocks which the broker desires to quote is increased or reduced, the corresponding required number of sections may be increased or decreased without interfering with the more permanent sections, hence no wasted or unused sections or spaces are necessary on the board to insure the desired capacity for future purposes. Since the indicating units and groups thereof may, according to this invention, be standardized and may be quickly interchanged even by an inexperienced person, only a small number of "spares" need be provided for replacements or additions in emergencies.

With the form of demountable construction hereinafter described, the electrical connections to the board may be made flexible and quickly detachable, and this, together with the demountable form of units, makes it possible for the broker to exhibit the stocks on his board in any desired arrangement and to change such arrangement from time to time without difficulty to suit his customers' demands or varying market conditions.

Also, according to this invention, the groups of indicating units and the units themselves may be demounted without necessarily obtaining access to the rear of the board and without disturbing the multitude of connection wires to other sections and units. Also, since the units are interchangeable, those which exhibit the more rapidly fluctuating stocks, if desired, may be occasionally interchanged with indicating units of inactive stocks, whereby there will be less tendency for particular units to become worn out before others.

The quotation board here described may have its quotation indicating units interchangeably connected to selecting apparatus, as for example in the manner disclosed in the copending United States patent application of Robert L. Daine, filed September 17, 1927, Serial No. 220,244, entitled Methods and apparatus for indicating quotations or other items. Patent No. 1,658,516 of February 7, 1928. The selecting apparatus and actuating circuits with which such a board may be operated may be of various forms, such for example as that described and claimed in the copending application of

Francois Favarger, filed January 16, 1923, Serial No. 613,012, entitled Electrical impulse transmitting devices, and the pending patent application in Switzerland of Fabrique D' Appareils Electriques Favarger S. A., of Neuenburg, Switzerland, No. 47,911, filed April 5, 1927 upon which the copending United States application of Frischknecht et al. Serial No. 267,680, filed April 5, 1928, is based.

Referring to Figs. 3, 4 and 6, the details of construction of the indicator units here shown will now be further described.

The digits to be exhibited may be arranged as at 28, around the periphery of rotatable drum members as 29, which may be enclosed within frame members as at 30. Within each of the frame members an operating magnet as at 31 may be mounted to cooperate with an armature member 32, pivotally mounted as at 33; a leaf spring 34 engaging a suitable stop member as at 35 may be secured to the armature 32 to normally retain the same in a position spaced from the core of the magnet 31. Each of the drums 29 may be secured in respect to a star wheel as at 36, which in turn is designed to engage an operating fork or pawl member 37, secured to and operated by the armature 32. The star wheel 36 and operating fork 37 are preferably of the particular shapes and relative dimensions substantially as shown in Fig. 4, and the same are designed to cooperate in a manner such that with each movement of the armature and the fork member 37, the star wheel 36 together with the drum member 29 is advanced always in the same direction through an angle subtended by the space between two teeth of the star wheel. The star wheel preferably has a number of teeth equal to the number of digits or digit spaces to be exhibited at the periphery of the drum and in the example shown eleven teeth are used, providing for ten digits and a blank space. Accordingly, whenever an electrical impulse is transmitted through the magnet the drum is advanced through such an angle as to remove from exhibition one digit, and to exhibit the next succeeding digit or space.

For normal operation of the unit, current may be supplied to one winding of the magnet through a pair of terminals, as for example, at 38 and 39. However, when a quotation is to be changed, it may be found to be expedient to first restore the indicating unit or a group of such units to a zero position or position of rest. For this operation a separate circuit including a second winding may be applied to the magnet 31, which circuit may either be brought in through two independent terminals, or as in the form illustrated in the drawings, one additional terminal 40 may be used, in conjunction with one of the terminals 38 or 39

acting as a return conductor common to both circuits.

The terminal 40 may be connected to the winding of the magnet by way of a circuit breaker, comprising a pair of cooperating spring contacts 41. To actuate the members 41 a contact operating member 42 may be pivoted to the frame as at 43 and formed with an extension 44 for engaging an insulating stud 45 which acts to separate the contacts at 41 whenever the member 42 engages the same. The member 42 may also be provided with a cam portion 46, normally resting against a stop pin 47 affixed to the frame, but such cam portion is also arranged to be engaged once during each revolution of the drum by a detent at 48 mounted to rotate with the drum 29. The detent 48 is so placed that when the drum exhibits either a blank space or its zero as desired, the detent will engage the contact operating member 42 and cause the same to separate the contacts at 41. At other times the contact operating member rests against the stop member 47 permitting the contacts at 41 to remain in closed circuit position.

With the above described construction a series of impulses may be sent through the circuit of terminals 38 and 39 to rotate the drum to exhibit the desired digit. Thereafter, when it is desired to change the exhibit, a series of, say, 11 impulses may be applied to the circuit of terminal 40 and such impulses will be effective in operating the magnet and turning the drum with a step-by-step movement until the drum arrives at the zero position, whereupon the contacts 41 will be separated and the circuit broken through the magnet 31 rendering the circuit of terminal 40 ineffective to further actuate the drum until after the same has been reset as desired by impulses through the circuit of terminals 38 and 39. The details of this indicator and the electrical circuits for controlling the same, except for the features hereinafter claimed, form no part of the present invention but are described and claimed in the copending application of Frischknecht et al. Serial No. 258,219, filed March 1, 1928.

As shown in Fig. 3, the frame portions, or casings 30 of the group of 4 indicating units may be arranged side-by-side and attached by suitable screws, etc., passing through lugs as at 49, for affixing the units to a mounting plate as at 50 (see Fig. 9). The group of 4 indicating units when thus assembled will be readily handled as a single quotation unit. In order that such unit may be quickly inserted or removed from a section of the board without particular attention being paid to the contacts, a quick-detachable contact arrangement, as best shown in Figs. 3 and 4, may be used and will now be described.

Insulating strips as at 51 may be affixed within the board sections at the rear of each

group of indicating units. Within such strip a plurality of cooperating pairs of contact terminals as at 52 may be mounted, a number of such terminals being provided equal to the number of terminals on the indicator units. Each of the indicating units may be provided with an insulation contact supporting portion 53 upon which the terminals as at 38, 39 and 40 may be mounted so as to be slidably embraced by the cooperating spring terminals 52 when the group of indicating units is slid into place. In this manner dependable, quick-detachable connections are provided for all of the terminals for each group of units.

15 Referring more particularly to Fig. 2, it will be noted that from each pair of terminals 52, connection wires as at 54 may be provided, to a quick-detachable plug member 55, which is shown and described in full detail in the above mentioned patent to Robert L. Daine. From the detachable plug members 55 flexible cables or lead wires 56 may extend to the selecting or other apparatus as above referred to.

20 25 Referring to Fig. 7, a board section 57 is here shown comprising an outer frame formed of suitable angle irons and of such shape that several of such frames may be readily placed either side by side or one on top of another. The section may be subdivided vertically into compartments one for each stock, by vertical partitions as at 58; each of such partitions may be formed with 30 35 struck-out lugs as at 59, such lugs forming as shown, means for slidably engaging the indicating unit supporting plates 50, and also forming supporting means for the contact supporting strips 51. The general arrangement of the indicator units mounted in operating position is shown in the drawings as is also the detachable plug member 55 and the quick-detachable contacts at 52.

40 45 Spaces for receiving slips indicating the previous day's quotations may be provided at indicated at 60. The front of the section may be provided with a suitable facing panel 61 having openings opposite each of the indicating units.

50 55 In Figs. 9, 10 and 11 a modified construction of sectional frame work is illustrated, comprising section frames as at 62 having vertical supporting strips 63. In this instance angle irons as at 64 may be welded or otherwise secured to the strips 63 for slidably receiving the indicator mounting plates 50 as well as the insulation contact supporting strips 51.

60 65 With the sectional indicator board provided by this invention, the proprietors of brokerage houses may also provide an additional service to such of their customers as have private offices. That is, each of such customers who may be interested principally in a relatively small number of stocks may have their

70 75 private offices equipped with one or more indicator board sections controlled from the same source as the main broker's board of the establishment. Indicators of these additional board sections are preferably made interchangeable in accordance with the invention of the above mentioned patent to Robert L. Daine. In this manner the special customers may be provided with an indicator board of almost universal flexibility as to service provided, yet such board may be of relatively small dimensions.

80 85 Further modifications of the invention are shown in Figs. 12-18 in which compartments are provided for digit indicators. As shown in Figs. 12 and 17, four of such compartments as at 65 may be arranged in side-by-side relationship within a single container 66 designed to be slidably received between division plates as at 67, which in turn form a part of a section frame. Electrical impulses for operating the indicators may be conducted thereto through a flexible cable as at 68 passing through the rear wall of the compartments 66 and substantially permanently affixed in respect thereto in any suitable manner, such as indicated at 69. The numerous wires within the flexible cable may be either permanently or detachably secured to their respective indicators as at 70. With this form of construction, the front of the indicator board may be made smooth and continuous as at 71 except for the openings 72 for exhibiting the digits. This form of construction is particularly adaptable to broker's boards which are accessible from the rear, inasmuch as the digit indicators for one quotation as contained within one of the compartments 66 may be slid out of the indicator board frame toward the rear and the electrical connections through the cable 68 need not be disturbed. With this arrangement indicators may be interchanged at various parts of the broker's board to enable the broker to rearrange the display of the stock quotations and such rearrangement may be secured either with or without interchangeability of the particular items quoted, according to the above mentioned Daine patent. If desired, the indicators per se may be made to be removable from the front of the compartments 65 after the compartments 66 have been removed from the broker's board, or if desired, the four separate indicators may be substantially permanently mounted within the compartments 65, in which case all separable contacts at the broker's board itself may be eliminated. With this construction a broker's board may be rearranged and repaired from the rear without the workman's obscuring the view at the front of the board and also, if merely rearrangement of the stocks on the board is desired, no electrical connections need be changed.

90 95 100 105 110 115 120 125 130 In Fig. 13 the rear view of part of an as-

sembled broker's board is indicated showing the manner in which four of the compartments or containers 66 may be arranged, one on top of another, to provide for the four quotations for one stock, namely the "Open", "High", "Low" and "Last" quotations. The construction of the containers and their arrangement in the board is also clearly shown in Fig. 17. If desired, the cables 68 as running to each quotation may be joined to form a larger cable 73 individual to one stock or other item.

Figs. 14, 15 and 18 illustrate a modified arrangement similar to that of Figs. 12, 13 and 17, except that the indicators for one stock or other item may be all placed within a single container as at 74 having four smaller subcompartments, 75. The subcompartments in turn are each designed to contain the four digit indicators necessary for one quotation. In this instance, a single cable 76 providing for electrical circuits of all of the indicators for one stock may be substantially permanently affixed in the compartment 74 in the manner shown.

Fig. 16 illustrates the front view of a broker's board as embodying the modifications of either Figs. 13 or 15. This figure also illustrates a different arrangement of the board sections. Sections of the broker's board which are to be filled with the digit indicators are indicated at 77. In some instances, for the sake of economy of space, brokers may prefer not to exhibit previous days' quotations, and to provide for such cases the board sections as at 78 upon the face of which "yesterday's" quotations are posted, may be made separate and detachable from the section 77, the section 78 being eliminated if the broker so chooses.

In the first modification above described, the board sections were provided with spaces for the indicia denoting the stocks quoted. If desired, according to the construction shown in Fig. 16, such indicia may be applied to board sections as at 79 which are also constructed independently of the sections 77 and 78. With the indicia thus on separate sections, changes in the markings may be much more conveniently effected, since it will be possible for an indicia section to be prepared with the desired characters painted or otherwise affixed thereon, and the old indicia section may be slid out and the new indicia section inserted substantially without interruption of the operation of the board. Furthermore this construction permits digit indicator sections to be used interchangeably with various indicia sections so that ample provision may be made for all contingencies and the broker's desires, as to the indicia, without making it necessary to maintain on hand an extra quantity of the indicator sections. Also, in some forms of construction, it may be found advisable to utilize the space

within the sections 78 and 79 for the operating circuit wires.

As is indicated in all of the above-described examples, we find it desirable to divide the broker's board into sections of such dimensions that each section will comprise the necessary indicator units for the quotations of a relatively small number of stocks arranged in a single horizontal row. It is customary on broker's boards to arrange in a vertical tier the various quotations, such as "Open", "High", "Low" and "Last", for each stock. The space necessary for such quotations for one stock, together with the space required for yesterday's quotations and the control wires and devices, is such as to be substantially equivalent to the desirable height of board section. Therefore, with the preferred embodiments of the invention as here disclosed, each section comprises the indicators for the quotations of a single horizontal row of different stocks. Inasmuch as the space necessary for each stock is considerably greater in its vertical dimension than in the horizontal direction, and while on the other hand the space available in broker's offices is generally greater in its horizontal dimension than in its vertical dimension, for this additional reason we find it preferable to limit the height of the sections to that necessary for the quotations for one stock rather than providing for a plurality of stocks one above another in each section. Substantially the widest possible range of flexibility of arrangement of the broker's board to fit the spaces generally available, therefore, is assured by the constructions shown.

The usual practice as followed in the design of sheet metal frame work and the like constructions may be here followed as to constructional details which are not specifically referred to herein.

While the invention has been described in detail with respect to particular preferred examples thereof which give satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent of the United States is:

1. A broker's quotation board comprising a plurality of frame sections, each having a plurality of vertical partitions dividing the section into spaces, each such space corresponding to a particular stock or other item; a plurality of horizontal shelves subdividing each of such spaces to provide sub-compartments each corresponding to a particular quotation such as "Open", "High", "Low" and "Last" of a certain stock or item, and a

plurality of electromagnetically operated indicating devices slidably received within each of said sub-compartments respectively for indicating the various digits of each quotation as the same fluctuates, each of said devices being an assembled unit separable as such from the others.

2. An automatic electromagnetically operated broker's board for indicating stock quotations or other like items comprising a framework having supported thereon a multitude of electromagnetically operated rotatable digit indicators relatively quickly detachable from said framework and interchangeable one with another, said indicators having contacts for their respective operating circuits arranged for quick-detachable engagement with cooperating contact terminals relatively permanently mounted on the framework, a plurality of multi-contact circuit disconnecting devices mounted on the framework, one of such devices being individual to each group of indicating devices for one stock or other item and mounted adjacent thereto, and electrical connections from said devices to said contact terminals for their respective associated indicators.

3. An automatic electrically operated broker's quotation board comprising a plurality of substantially similar and interchangeable sections, separable from each other as assembled units and each carrying a plurality of electromagnetically operated indicators for exhibiting fluctuating quotations of a number of different stocks or other items, said indicators being arranged in a plurality of groups, each group individual to one stock or like item, and providing a vertical tier of several quotations pertaining to each such stock or item, and each of said sections comprising a single horizontal row of such groups of indicators.

4. An automatic electromagnetically operated broker's quotation board comprising a plurality of sections separable from each other as assembled units and each carrying means for exhibiting at one time fluctuating quotations of several different stocks or other items, said sections being designed to be superposed in tiers to form the broker's board, and independent board sections carrying changeable exhibitors for displaying "Yesterday's" quotations corresponding to each stock or item, said last named sections being insertable between said superposed first named sections.

5. An automatic electrically operated broker's quotation board comprising a plurality of substantially similar interchangeable and relatively separable frame sections, each such section carrying a plurality of substantially similar interchangeable quick-demountable electromagnetically operated indicators for exhibiting fluctuating quotations of a num-

ber of different stocks or other items, said indicators being positioned in the front portions of said sections, terminal contacts within said sections for quick-detachable engagement with cooperating contacts on the indicators, and relatively permanent connections within the rear portions of the section frames running from said terminal contacts to groups of section terminals, a group of such section terminals being provided individual to each group of indicators for one stock or other item.

6. An automatic electrically operated broker's quotation board comprising a multitude of similar interchangeable quick-demountable indicating units for respectively exhibiting the several digits of the various quotations, a supporting frame having compartments individual to each quotation, the several indicating units for each quotation being carried in such compartments side by side in close relationship to cooperate in giving a legible quotation, and said indicating units having contacts for their respective operating circuits arranged for quick-detachable engagement with corresponding cooperating contact terminals within the compartments, whereby the several indicators for the digits of one quotation may be quickly removed or replaced and whereby also any individual digit indicator may be independently and quickly replaced by another.

7. Indicating apparatus comprising a plurality of electrical indicator units, each having rotatable character display drums, a supporting frame for slidably receiving said indicator units to support the same in spaced groups so that the characters displayed cooperate to exhibit a plurality of quotations or other information, apertured masks individual to each of said indicator units and mounted thereon whereby the characters to be exhibited are exposed at the apertures, while other characters on the drums are concealed from view by the masks, and additional masking means common to a plurality of groups of indicator units and located in front of said first named masks, to cover spaces between the indicator units of a group and between the groups of indicator units and to prevent slidable removal thereof.

8. A broker's quotation board construction comprising a large number of electromagnetically operable rotatable digit indicating drums, supporting means for mounting said drums in suitable spaced relationship whereby digits will be exposed at the face of the broker's board to indicate quotations of numerous stocks or other items, the drums for each stock or item being arranged in a group, a multi-contact disconnectable terminal device individual to each of said groups and through which the control circuits therefor are operated, and means on the face of the board for identifying each of said groups of

drums, the space to the rear of said identifying means being occupied by said multicontact terminal device.

9. A broker's quotation board construction comprising a large number of electromagnetically operable rotatable digit indicating drums, supporting means for mounting said drums in suitable spaced relationship whereby digits will be exposed at the face of the broker's board to indicate quotations of numerous stocks or other items, the drums for each stock or item being arranged in a group, a multicontact disconnectable terminal device individual to each of said groups and through which the control circuits therefor are operated, means on the face of the board for identifying each of said groups of drums, the space to the rear of said identifying means being occupied by said multicontact terminal device, and a plurality of apertured masks for forming the face of the board, said masks carrying said identifying means and covering the spaces between said groups of drums.
- 25 10. A broker's quotation board comprising a plurality of groups of closely spaced rotatable digit indicating drums, one such group being provided for each stock or other item, electromagnetic operating means occupying the space to the rear of said drums, a group of manually changeable indicia on the face of the board adjacent each of said groups of drums, and a multicontact disconnecting device for the circuits of the operating devices for each of said drum groups, said multicontact devices respectively occupying the spaces to the rear of said manually changeable indicia.
- 30 11. The combination of a stock quotation board comprising vertical and horizontal walls defining compartments, a plurality of sets of indicators for indicating the price ranges of a stock, and a container for each of said sets of indicators slidably and removably mounted in one of said compartments.
- 35 12. The combination of a stock quotation board comprising vertical and horizontal walls defining compartments, a plurality of groups of sets of indicators each group indicating the various price ranges of a stock, and a container for each group of indicators mounted slidably and removably in one of said compartments.
- 40 45 50 55 In testimony whereof we have signed our names to this specification.

ROBERT L. DAINE.
RENÉ GUYÉ.
